DES. 2066

Letters Patent No. 2066-Dated May 16, 1866.

Design for a Trademark.

The schedule referred to in these Letters Patent and making part of the same.

To all whom it may concern:

Be it known that J. E. Lowell, of Portland, in the County of Cumberland and State of Maine, have originated and invented a new design for a trademark, of which the following is a full, clear and exact description, reference being had to the accompanying drawings or specimens, making part of these specifications, in which-

Fig. No 1 represents an example of my design as colored.

Fig. No 2. the same with colors.

The object of my invention is to produce a trade mark, to be used by me to stamp certain articles of manufacture by me made, or the receptacles in which they are contained.

My invention consists of certain figures or designs represented at fig. 1 and 2, in the accompanying drawings and hereinafter enumerated and described, included within lines drawn as to form a diamond or rhombus. The outer one of these lines is heavier and broader than the inner. Within the lines thus described and drawn are the figures of a cap and a lion. Around the lower edge of the cap there is represented a band in width about one-half the height of the cap, curved at the upper edge and decorated with black. Upon the band are represented four triangles, each having three and one with two of each leaves. The ends of

DES. 2066

and are not represented to meet at the cap, but project separately
and are brought to points behind the same. The cap thus described is
surmounted with the figure of a lion three of whose feet are resting upon
the cap, the fourth is held in a horizontal position.

The design may be used with colors as in fig. 1, or
without as in fig. 2.

When it is desired to be used with colors, the colors are
the figure of the lion a light brown, the cap vermilion and the
band a light yellow.

What I claim as my invention and desire to secure
by Letters Patent is—

The design for a trademark herein set forth and
described.
